UNITED STATES PATENT OFFICE.

NELSON W. TWISS, OF NEW HAVEN, CONNECTICUT.

VALVE-GEAR.

SPECIFICATION forming part of Letters Patent No. 350,172, dated October 5, 1886.

Application filed February 19, 1884. Serial No. 121,350. (No model.)

To all whom it may concern:

Be it known that I, NELSON W. TWISS, a citizen of the United States, residing at New Haven, in the county of New Haven and State of Connecticut, have invented certain new and useful Improvements in Automatic Cut-Offs for Steam-Engines, of which the following is a description.

My invention relates to cut-off mechanisms for steam-engines, and is an improvement upon an invention for which Letters Patent of the United States No. 212,285 were granted to me on the 11th day of February, 1879.

In the mechanism described in the patent referred to the cut-off valve was arranged within and concentric with an oscillating main valve, which turned in a cylindrical valve-chamber. The cut-off valve was adapted to oscillate within the main valve, and had its stem or shaft passed axially through the hollow stem of the main valve. The cut-off valve was arranged to disengage from the driving-gear at the point of cut off and closed by the action of a spring.

My present invention consists in a novel improved closing device for operating the valve, as hereinafter more fully described, and particularly pointed out in the claims.

In the accompanying drawings, Figure 1 is an end view of the valve stems and cranks fitted with my improved closing device. Fig. 2 is a central vertical section through Fig. 1, and Fig. 3 shows the device with the inclosing-case omitted.

Referring to the drawings, L designates the cut-off-valve crank, and F' denotes the main-valve crank, which parts are fully described and shown in the patent referred to. A pin, a', is inserted in the face of the main-valve crank and projects through a slot, b', in the cut-off-valve crank. A spiral spring, c', is coiled loosely around the valve stem or shaft G, and is inclosed by a cylindrical cup or case, E', which is fastened upon the end of the shaft by means of a set-screw, d'. The set-screw passes radially through the cup near its closed end, and through an internal hub, x, formed on the end of the cup around the shaft. The hub enters the end of the coiled spring, and a corresponding hub on the cut-off-valve crank enters the opposite end of the spring, by which

means the coil is kept at a sufficient distance from the cut-off-valve stem to allow it to contract. The spring is preferably wound so that its tension is in the direction to contract the coil diametrically. The outer end of the spring is bent parallel with the valve stem or shaft and adapted to bear against the set-screw d'. The opposite end of the spring is hooked around the pin a', and when the case is properly adjusted on the valve-stem the spring acts against the set-screw and the pin in the direction to turn the valve-crank and close the cut-off valve. The end of the spring which bears against the set-screw may bear instead against a suitable projection at the end of the cup, if desired. Any required tension may be given to the spring by turning the cup around on the stem in the direction to apply strain to the spring, and fastening it when adjusted by means of the set-screw d'. The advantage of this closing device is, that it employs a spring which may be made of any required length and corresponding elasticity, that the spring is entirely incased and guarded by the cup or case, and that its tension may be easily regulated, as desired.

It is evident that the inclosing-case may be attached to the main-valve crank, or may be entirely dispensed with, if desired, in which case the hub x may have a projecting flange, k, formed upon it, with a slot, n, to receive the bent end of the spring c', as shown in Fig. 3. With this modification the tension of the spring is adjusted by turning the collar upon the shaft 85 the same as the entire case is turned in the other form of the device.

I claim as new and desire to secure by Letters Patent—

1. In automatic valve-gearing having an oscillating cut-off valve within and concentric to the main valve, the combination, with the valve stems or shafts, of a spiral spring coiled around the cut-off-valve stem and arranged to act torsionally on the respective valve-stems and the cut-off valve, and a cup or case inclosing the spring and secured upon the cut-off-valve stem, substantially in the manner and for the purpose described.

2. The combination of the cut-off-valve stem or shaft G, the main-valve crank F', the cylindrical cup or case E', secured on the valve-

stem, and the spiral spring *c'*, inclosed within the case, coiled around the cut-off-valve stem, secured to the main-valve crank, and adapted to act on the cut-off-valve stem in the direction to close the valve, substantially in the manner described.

3. In automatic valve-gearing having an oscillating cut-off valve within and concentric to the main valve, the combination, with the 10 valve stems or shafts, of a spiral spring coiled around the cut-off-valve stem and arranged to

act at one end torsionally on the main-valve crank, and an adjustable collar clamped upon the cut-off-valve stem, and having a projection or abutment upon which the opposite end of 15 the spring acts to close the valve, substantially in the manner and for the purpose specified.

NELSON W. TWISS.
